UNITED STATES PATENT OFFICE.

ARTHUR J. COCHRAN, OF COLUMBUS, INDIANA.

DAUBER, POLISHER, &c.

1,384,827.

Specification of Letters Patent. Patented July 19, 1921.

Application filed June 10, 1920. Serial No. 387,921.

To all whom it may concern:

Be it known that I, ARTHUR J. COCHRAN, a citizen of the United States, residing at Columbus, in the county of Bartholomew 5 and State of Indiana, have invented a new and useful Dauber, Polisher, &c., of which the following is a specification.

The object of my invention is to produce cheaply an efficient article for the reception, 10 holding and manipulation of a polishing or daubing member, the article being particularly useful as a shoe polisher or dauber, a window cleaner, furniture duster, etc.

The accompanying drawings illustrate my 15 invention. Figure 1 is a perspective view of the article with the cloth element omitted; Fig. 2 a similar view showing the cloth in position.

In the drawings, 10 indicates a main body 20 which may be conveniently formed of wood, hard rubber, etc., said main body being formed to provide a support 11, two flanking pockets 12 and 13, a retaining shoulder 14, and a retaining shoulder 15. Secured to 25 the supporting surface 11 is a strip of flexible material 16, which is preferably not only flexible but slightly longitudinally compressible, the most convenient material probably being scrap leather.

30 The piece 16 is so secured upon the surface 11 that its inner end will project across pocket 12 and will lie closely adjacent shoulder 15, while its opposite end projects to

any desired extent in the forward end of the main body 10.

Any piece of suitable cloth, such, for instance, as felt, heavy woolen cloth, etc., may have one end passed into pocket 12 over the end of member 16, so that it will be firmly held in place between the inner end of member 16 and shoulder 15. The cloth may be now drawn forwardly over member 16 and the outer end of this member flexed and the end of the cloth drawn backwardly and tucked into pocket 13, where it will be firmly 45 retained. Any scrap cloth may be readily applied in the manner stated, and the article in this condition used for many purposes which will readily suggest themselves.

I claim as my invention:

As an article of manufacture, a main body provided with a downwardly extended support, flanking pockets and a retaining shoulder adjacent each pocket, and a flexible tongue secured to the support and extending into proximity with the shoulders whereby a flexible strip may be applied to the tongue and retained thereon between the tongue and shoulders, substantially as described.

In witness whereof, I have hereunto set my hand at Indianapolis, Indiana, this 7th day of June, A. D. one thousand nine hundred and twenty.

ARTHUR J. COCHRAN.
